CAR TRUCK

Walter H. Baselt, Chicago, Ill., assignor to American Steel Foundries, Chicago, Ill., a corporation of New Jersey

Application December 5, 1940, Serial No. 368,617

21 Claims. (Cl. 105—197.2)

My invention relates to a four wheel railway car truck and more specifically to a novel method of resiliently maintaining the relative position of the parts thereof.

In recent types of four wheel spring plankless trucks guide surfaces are provided on the ends of the bolster to engage guide surfaces on the side frames for the purpose of maintaining the proper running position of the parts of the truck as a whole. While this type of truck has been found satisfactory, nevertheless, a certain amount of chafing or wear may occur between the guide surfaces and an arrangement to substantially eliminate all such chafing would be an improvement and this I have accomplished in my novel form of truck.

An object of my invention is to afford a novel draft connection between each side frame and the adjacent end of the bolster in such manner as substantially to eliminate all chafing between the end of the bolster and the associated side frame.

My novel arrangement comprehends a form of connection between the projecting end of the bolster and a remote point of the associated side frame with a degree of rigidity which reduces to a minimum the play of the bolster end in the bolster opening of the side frame.

My novel connection is through resilient means which eliminates metal-to-metal contact and greatly reduces wear of adjacent parts and the concomitant noises resulting from such wear. In my novel form of side frame, it is practical to eliminate the column guide lugs which normally engage the outboard face of the side frame columns, but I have retained the inboard guide lugs.

In addition to the above-mentioned features, my novel arrangement is so designed as to accommodate the quick wheel change feature which is highly desirable under present conditions where rapid wheel change is necessary in order to accommodate the present rapid freight train schedules.

Specifically, my novel truck comprises a rigid rod and tube connection resiliently connected between the projecting end of the bolster and a bracket integrally formed on the outboard face of the side frame adjacent the journal box at one end of said frame. Such a draft rod may be associated with each side frame at diagonally opposite ends of the truck for opposite sides thereof, thus assuring adequate aligning means for the truck as a whole while, at the same time,

substantially eliminating wearing along column surfaces as already described.

Referring generally to the drawings,

Figure 1 is a fragmentary top plan view of a four wheel truck structure embodying my invention, only one-quarter of the truck being shown.

Figure 2 is a side elevation of the truck structure shown in Figure 1.

Figure 2A is a fragmentary sectional view through the side frame adjacent the draft rod connection substantially in the vertical plane indicated by the line A—A of Figure 2.

Figure 3 is a sectional view through the truck arrangement shown in Figures 1 and 2 taken substantially in the vertical plane bisecting the truck transversely but showing in elevation the bolster and the draft rod connection.

Figure 4 is a top plan view of reduced size showing the method of application of my novel form of draft rod to opposite sides and alternate ends of the truck structure.

Describing the structure in detail, my novel truck arrangement, as illustrated, comprises spaced truss type side frames 2 and 4 (Figure 4) each having a compression member 6 and a tension member 8 merging at their opposite ends with integrally formed journal boxes 10, 10 and joined intermediate their ends by the integral spaced columns 12, 12 defining therewith the bolster opening 14 through which may project the adjacent end of the transverse bolster or load carrying member 16. Each side frame may have the usual brake hanger brackets 18, 18 integrally formed on the inboard face thereof adjacent the junctures of the columns with the compression member. On the widened spring seat portion 20 of the tension member beneath the bolster opening 14 may be positioned any desired form of spring group arrangement, here shown as comprising a bottom spring plate 22, a top spring plate 24 with coils or other forms of resilient support diagrammatically indicated at 26, 26 and upon said spring group may thus be resiliently supported the adjacent end of the bolster 16. The bolster is formed with inboard guide lugs 28, 28 for abutment against the inboard edges of the guide columns, but the usual outboard guide lugs are omitted from the bolster. Instead of using such outboard guide lugs, I have formed on each end of the bolster projecting beyond the outboard face of the side frame a novel means of connection to a resilient draft rod generally designated 30. The projecting end of the bolster is formed with an integral

vertical plate or rib 32 in the plane bisecting the bolster longitudinally and coinciding with the plane bisecting the truck transversely, said plate being generally circular in form with the annular flange 34 defining a slight recess formed on one face thereof. Said plate is slotted as at 36 for reception of the securing bolt 38 associated with the rod 30. The draft rod 30 comprises the rigid outer tube 40 with the face plates 42, 42 on opposite ends thereof affording convenient abutment means for the resilient pads 44, 44 which may be compressed between the plates 42, 42 and the washers 46, 46, said washer 46 at one end of the draft rod bearing against the adjacent face of the bolster plate 32. The securing bolt 38 extends through the rigid rod 40 and through the bolster plate 32, and over the projecting end of the securing bolt 38 may be placed the washer 48 positioned by means of the flange 34 and between the washer 48 and the end washer 50 may be compressed the rubber pad 52. At the opposite end of the draft rod, the washer 46 is seated against the inner face of the vertical web 54 slotted as at 55 and forming a part of the integral side frame bracket generally designated 56. On the opposite face of the web 54 is formed an annular flange 58 defining a slight recess within which may be positioned the washer 60. Between the washer 60 and the spaced end washer 62 may be compressed the rubber pad 64 and the threaded nuts on the ends of the securing bolt 38 may be drawn up to afford any desired degree of rigidity between the side frame bracket and the projecting end of the bolster. The thickness of the resilient pads 44, 44 and the resistance to compression offered by them are factors in fixing the rigidity of the connection.

It will thus be seen that my novel arrangement affords a somewhat resilient method of connecting the bolster and side frames. In this novel arrangement, the bolster as originally assembled with the side frame may be properly adjusted to the exact center of the bolster opening and, as already suggested, the desired degree of rigidity may be applied to maintain the bolster substantially in said central position. Any tendency of the truck to misalign will be resisted by a further compression of the rubber pads and when the truck becomes slightly misaligned, this force will tend to restore the parts to normal position.

To those skilled in the art, it will be readily apparent that in order to change wheels it is only necessary to disconnect the draft rod from the end of the bolster after which the side frame may be removed in order to permit wheel change. In the dismantling operation, it is necessary, of course, to disconnect both ends of the draft rod, and the bracket on the side frame as well as the integral securing plate on the end of the bolster are slotted particularly for that operation.

It is understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. In a spring plankless quick wheel change four wheel railway car truck, spaced side frames having bolster openings, spring groups at the bottom of said openings, a bolster seated on said spring groups and extending between said frames with guide lugs abutting the inboard faces of

said frames and ends projecting outboard thereof, brackets on said side frames at diagonally opposite corners of the truck, and a resilient connection between the side frame bracket and the bolster end at each side of the truck, said resilient connection comprising a rigid bar resiliently and adjustably secured between the bracket and the bolster end, each of said bolster ends when disconnected from said rigid bar being freely removable through the adjacent bolster opening while the supporting spring group remains in assembled relationship with the associated side frame.

2. In a spring plankless four wheel railway car truck of quick wheel change type, spaced side frames having bolster openings, spring seats beneath said openings, spring groups positioned thereon, and a transverse load carrying member seated on said spring groups and connecting said frames, said load carrying member having inboard guide lugs engaging guide columns on said frames and having end portions projecting outboard said bolster openings, brackets on the outboard faces of said frames at diagonally opposite corners of the truck, and rigid means resiliently connected between the brackets and the bolster ends at opposite sides of the truck, said bolster ends when disconnected from said rigid means being freely removable from said bolster openings while said spring groups remain in assembled relationship with said side frames.

3. In a spring plankless four wheel railway car truck of quick wheel change type, spaced side frames having bolster openings, spring seats beneath said openings, spring groups positioned thereon, and a transverse load carrying member seated on said spring groups and connecting said frames, said load carrying member having inboard guide lugs engaging guide columns on said frames and having end portions projecting outboard said bolster openings, brackets on the outboard faces of said side frames at diagonally opposite corners of the truck, and rigid means resiliently connected between the brackets and the bolster ends at opposite sides of the truck to retain said side frames and bolster in assembly.

4. In a spring plankless quick wheel change four wheel railway car truck, spaced side frames having bolster openings, spring groups at the bottom of said openings, a bolster seated on said spring groups and extending between said frames with guide lugs abutting the inboard faces of said frames and ends projecting outboard thereof, brackets on said side frames at diagonally opposite corners of the truck, and a resilient connection between the side frame bracket and the bolster end at each side of the truck, said resilient connection comprising a rigid member between the bracket and the bolster end, resilient means interposed between respective ends of the member and the bracket and bolster end, and clamping means for compressing said resilient means.

5. In a railway car truck, a truss side frame having a bolster opening, a spring group seated on said frame at the bottom of said opening, a bracket on the outboard face of said frame, and a bolster end positioned on said spring group and tied to said frame by guide lugs on said bolster abutting the inboard face of said frame and by a rigid bar resiliently connected with said bolster end and said bracket, the connection of said bar being adjustable to maintain said bolster end centrally in said bolster opening, said bolster end being freely removable from said opening when

disconnected from said bar while said spring group remains in normal assembled position.

6. In a spring plankless four wheel railway car truck of quick wheel change type, spaced truss type side frames having bolster openings, spring groups at the bottom of said openings, a bolster seated on said spring groups with ends projecting outboard said openings, brackets on the outboard faces of said side frames at diagonally opposite corners of the truck, and rigid means resiliently connected between the bracket and bolster end at each side of the truck, the connection of said means between each bracket and bolster end being adjustable to accommodate positioning of the bolster end centrally within the associated bolster opening.

7. In a spring plankless quick wheel change four wheel railway car truck, spaced side frames having bolster openings, spring groups at the bottom of said openings, a bolster seated on said 20 spring groups and extending between said frames with guide lugs abutting the inboard faces of said frames and ends projecting outboard thereof, brackets on said side frames at diagonally opposite corners of the truck, and a resilient connection between the side frame bracket and the bolster end at each side of the truck, said resilient connection comprising a rigid bar resiliently and adjustably secured between the bracket and the bolster end.

8. In a railway car truck, spaced side frames having bolster openings, spring groups seated on said frames at the bottom of said openings, lateral brackets on the outboard faces of said frames at diagonally opposite corners of said truck, a bolster positioned on said spring groups and tying said frames together, and a connection between the bracket and the projecting bolster end at each side of said truck, each of said connections comprising a rigid bar resiliently connected to said bracket and said bolster end, the connection being adjustable to maintain said bolster end centrally in said opening.

9. In a spring plankless four wheel railway car truck of quick wheel change type, spaced side frames having bolster openings, a bolster extending therebetween with ends projecting through said openings, lateral brackets on the outboard faces of said frames at diagonally opposite corners of the truck, and a connection between the bracket and the projecting bolster end at each side of the truck, each of said connections comprising rigid means extending between said bracket and bolster end, resilient members interposed between the rigid means and bracket and between the rigid means and bolster end, and means for adjustably compressing said resilient members.

10. In a spring plankless four wheel railway car truck of quick wheel change type, spaced side frames having bolster openings, a bolster extending therebetween with ends projecting through said openings, lateral brackets on the outboard faces of said frames at diagonally opposite corners of the truck, and a connection between the bracket and the projecting bolster end at each side of the truck, said connection comprising a rigid member extending between the bracket and the bolster end, resilient pads interposed between the respective ends of said rigid member and the bracket and bolster end, and adjustable means for compressing said pads.

11. In a spring plankless four wheel railway car truck of quick wheel change type, spaced side

5 frames having bolster openings, a bolster extending therebetween with ends projecting through said openings, lateral brackets on the outboard faces of said frames at diagonally opposite corners of the truck, a connection between the bracket and the projecting bolster end at each side of the truck, said connection comprising a rigid bar interposed between the bolster end and said bracket, and means for resiliently securing said bar to said bracket and end.

10 12. In a railway car truck, a truss side frame having a bolster opening, resilient means on said frame in said opening, a bolster end supported on said means, and a rigid bar tying said end to said frame, said bar being resiliently connected to said end and to the outboard face of said frame, and said bar being substantially the sole means preventing disassembly of the bolster by excessive inboard movement thereof with respect to said frame.

15 13. In a spring plankless four wheel railway car truck of quick wheel change type, spaced truss type side frames having bolster openings, spring groups at the bottom of said openings, a bolster seated on said spring groups with ends projecting outboard said openings, brackets on the outboard faces of said side frames at diagonally opposite corners of the truck, and rigid means resiliently connected between the bracket and bolster end at 20 each side of the truck.

25 14. In a four wheel railway car truck of quick wheel change type, spaced side frames having bolster openings, a bolster extending between said frames with ends projecting through said openings, brackets on the outboard faces of said side frames at diagonally opposite corners of the truck, draft rods connected between said brackets and the projecting ends of the bolster, respectively, and adjustable means to accommodate positioning of said bolster ends centrally within the associated bolster openings.

30 15. In a four wheel railway car truck of quick wheel change type, spaced side frames having bolster openings, a bolster extending between said frames with ends projecting through said openings, brackets on the outboard faces of said side frames at diagonally opposite corners of the truck, and draft rods resiliently connected between said brackets and the projecting ends of the bolster, respectively.

35 16. In a four wheel railway car truck of quick wheel change type, spaced side frames having bolster openings, a bolster extending between said frames with ends projecting through said openings, brackets on the outboard faces of said side frames at diagonally opposite corners of the truck, and compression bars resiliently connected between said brackets and the adjacent projecting bolster ends at respective sides of the truck.

40 17. In a spring plankless four wheel railway car truck of quick wheel change type, spaced side frames having bolster openings, a bolster extending therebetween with ends projecting through said openings, lateral brackets on the outboard faces of said frames at diagonally opposite corners of the truck, and a rigid bar resiliently connected between the bracket and the projecting bolster end at each side of the truck.

45 18. In a railway car truck, a truss side frame having a bolster opening, resilient means on said frame in said opening, a bolster end supported on said means, and means maintaining said frame and said end in assembled relationship and characterized by a rigid member resiliently

connected to said end and to said frame, said rigid member being the sole means preventing disassembly of said bolster by excessive movement thereof inboardly with respect to said frame.

19. In a railway car truck, spaced side frames having bolster openings, spring groups on said frames in said openings, a bolster seated on said spring groups, and means tying said bolster to said frames, said means comprising a rigid member resiliently connected to each end of said bolster, said members being resiliently connected to the outboard faces of the associated side frames, each of said rigid members being connected to one end only of the associated frame and constituting the sole means preventing disassembly of the bolster by excessive inboard movement thereof with respect to said frame.

20. In a railway car truck, a side frame having

a bolster opening, a bolster resiliently supported in said opening, and means maintaining said bolster therein, said means consisting of guide means on the bolster abutting the inboard edges

5 of the frame, and a rigid member resiliently connected to said bolster and to the outboard face of said frame, said rigid member being substantially the sole means operable to prevent disassembly of said bolster by relative inboard movement there-

10 of with respect to said frame.

21. In a bolster, a box-like structure comprising top and bottom and spaced side walls, a substantially vertical lug on the end of said bolster integrally formed with said top and bottom walls and disposed substantially in the plane bisecting the bolster longitudinally thereof, and a slot in said lug extending from the periphery to substantially the center thereof.

WALTER H. BASELT.
